UNITED STATES PATENT OFFICE.

HENRY R. FRISBIE, OF CHICOPEE FALLS, MASSACHUSETTS.

DESIGN FOR AN OIL-CAN BRACKET FOR SEWING-MACHINES.

Specification forming part of Design No. 6,320, dated December 24, 1872.

To all whom it may concern:

Be it known that I, HENRY R. FRISBIE, of Chicopee Falls, Hampden county, in the State of Massachusetts, have invented a Design for a Bracket, of which the following is a specification:

The nature of my design is fully illustrated in the accompanying photograph, to which reference is made.

The bracket is intended to hold an oil-can, such as is used with sewing-machines. It is formed of two arms of scroll-work depending from a horizontal upper straight bar, and has at the lower end a forked projection for embracing the neck of the oil-can.

Claim.

What I claim as my invention is—
The design for a bracket, substantially as above described.

HENRY R. FRISBIE.
